UNITED STATES PATENT OFFICE.

KARL AHLQUIST, OF RUGBY, ENGLAND, ASSIGNOR TO GENERAL ELECTRIC COMPANY,
A CORPORATION OF NEW YORK.

ROTARY COMPRESSOR.

1,080,743.

Specification of Letters Patent.

Patented Dec. 9, 1913.

Application filed May 17, 1910. Serial No. 561,813.

To all whom it may concern:

Be it known that I, KARL AHLQUIST, a subject of the King of Sweden, residing at Rugby, in the county of Warwickshire, England, have invented certain new and useful Improvements in Rotary Compressors, of which the following is a specification.

This invention relates to compressing apparatus generally and more particularly to multi-stage centrifugal compressors for providing a supply of elastic fluid, such as air under pressure.

To attain a high efficiency with a multi-stage centrifugal compressor it is considered necessary to cool the air, or other elastic fluid being treated, during the process of compression. This was generally done while the air was passing from one stage to the next and, to effectively cool it, it has sometimes been found necessary to carry the air outside of the compressor casing between the successive stages and to pass it through separate coolers in order to avoid the necessity of increasing the size of the compressor unduly.

The object of this invention is to provide a compressor of the above type which will have a high efficiency without increasing the size of the apparatus to any great extent, and to this end it consists in providing large radiating surfaces in the path of the fluid from one stage of the compressor to the next, said surfaces being provided with means for conducting away the heat taken from the fluid.

In the accompanying drawings which illustrate my invention, Figure 1 is a sectional side view of a portion of a compressor, Fig. 2 is a cross-sectional elevation on the line 2—2 of Fig. 1 and Fig. 3 is a developed section on the line 3—3 of Fig. 1.

In the drawings, 1 represents the impeller hubs carrying the moving blades 2. The air or other elastic fluid is discharged from the blades through fixed guide vanes 3 which partially convert the velocity of the fluid into pressure. After passing through these vanes the fluid is caused to pass between a number of ribs or webs 4 which project radially inward from the casing. These ribs are arranged on the inside of the casing on the principle of a screw-thread as clearly shown in Fig. 3 so that the fluid which issues from the vanes 3 at a considerable tangential velocity is screwed axially

relatively to the casing until it comes opposite the passage 5 in the diaphragm arranged between the stages, said passage leading to the next stage of the compressor. The ribs 4 are kept cool by surrounding the casing with a passage 6 through which water is circulated.

A compressor constructed as above described provides a large cooling surface for the air without greatly increasing the size of the compressor casing and the cooling is very effective owing to the high speed at which the air is caused to pass between the ribs. No material loss in pressure due to passage friction takes place as the residual tangential velocity of the fluid at the exit of the discharge vanes in any case will be to a large extent lost in friction and eddy currents before entering the next stage. The necessity of employing a separate cooling device is also obviated by this construction.

In accordance with the provisions of the patent statutes, I have described the principle of operation of my invention, together with the apparatus which I now consider to represent the best embodiment thereof; but I desire to have it understood that the apparatus shown is only illustrative, and that the invention can be carried out by other means.

What I claim as new and desire to secure by Letters Patent of the United States, is:—

1. A rotary compressor comprising a casing provided with a plurality of stages and an impeller for each stage, there being fluid conducting passages between the stages that are arranged within the casing and other passages within the casing for circulating a cooling medium, said cooling passages being provided with radiating members that project into the conducting passages.

2. A multi-stage rotary compressor comprising impellers, a casing therefor containing passages for conducting fluid from one stage to the next, and means also located within the casing for circulating a cooling medium and conveying away heat due to compression, said means including radiating ribs that extend into the conducting passages.

3. A multi-stage rotary air-compressor, having a casing containing ribs forming passages for conducting the air from one stage to the next, said ribs being adapted to absorb heat from the air.

4. A multi-stage rotary air-compressor, having a casing containing helically arranged ribs forming passages for conducting the air from one stage to the next.
5. A multi-stage rotary air-compressor, having a casing containing helically arranged ribs forming passages for conducting the air from one stage to the next, and a water jacket surrounding said air passages.
- 10 6. A rotary compressor comprising a casing divided into stages by diaphragms having passages through which the fluid flows from one stage to another, an impeller for each stage, and helical passages formed in the outer portion of the casing which receive the discharge from the impellers and direct it forwardly into the passages in the diaphragms.
7. A rotary compressor comprising a casing divided into stages by diaphragms having passages through which the fluid flows from one stage to another, an impeller for each stage, a plurality of parallel helical passages formed in the outer portion of the casing which receive the discharge from the impeller and direct it forwardly into the passages in the adjacent diaphragm, and means for cooling the walls of the passages.

In witness whereof, I have hereunto set my hand this seventh day of April, 1910.

KARL AHLQUIST.
